United States Patent Office

Des. 175,163
Patented July 19, 1955

175,163

HINGE

Charles S. Gehrie, Montclair, N. J., assignor to Presto
Lock Company, Garfield, N. J., a corporation of New Jersey

Application September 27, 1954, Serial No. 32,451

Term of patent 14 years

(Cl. D10—9)

Fig. 1

Fig. 2

Fig. 1 is a front face view of a hinge showing my new design; and

Fig. 2 is a side edge elevational view of the same.

I claim:

The ornamental design for a hinge, as shown.
